George C. Heilweil, ATTORNEY.

UNITED STATES PATENT OFFICE.

CHESTER MAJEWSKI, OF CHICAGO, ILLINOIS.

DESIGN FOR A NOVELTY CLOCK.

60,796.

Specification for Design.

Patented Apr. 11, 1922.

Application filed December 29, 1921. Serial No. 525,783. Term of patent 14 years.

To all whom it may concern:

Be it known that I, CHESTER MAJEWSKI, a citizen of the United States, and a resident of Chicago, in the county of Cook and State of Illinois, have invented a new, original, and ornamental Design for a Novelty Clock, of which the following is a specification, reference being had to the accompanying drawing, forming part thereof.

The figure is a perspective view of a novelty clock showing my new design.

I claim—

The ornamental design for a novelty clock as shown.

CHESTER MAJEWSKI.
